UNITED STATES PATENT OFFICE

BURT FROST UPHAM, OF BROOKLINE, MASSACHUSETTS, ASSIGNOR TO MILLER PRINTING MACHINERY COMPANY, OF PITTSBURGH, PENNSYLVANIA, A CORPORATION OF PENNSYLVANIA

DELIVERY STRIPPER FINGER

Application filed January 14, 1929. Serial No. 332,473.

My invention pertains to delivery stripper fingers for cylinder printing presses, that is to say, to the fingers ordinarily employed upon cylinder printing presses for disengaging the printed sheet from the cylinder and directing it to the tapes or other delivery contrivances.

Stripper fingers as heretofore constructed have presented continuous surfaces of material length over which the printed sheet has been required to slide in being delivered from the printing cylinder. The sheets, in their passage through the press or otherwise, frequently accumulate charges of static electricity which result in an attraction between the sheets and the stripper fingers and consequently a sticking action which sometimes hinders the proper operation of the press. This sticking action may cause a retaining of the leading edge of the sheet, whereby the sheet, especially a sheet of thin paper or tissue, is caused to buckle between the stripper fingers and the cylinder instead of maintaining a straight line in being delivered. Or the trailing edge of the printed sheet may adhere to the stripper fingers, with the result that the sheet remains on the delivery tapes, with its trailing edge stuck to the stripper fingers, instead of being delivered in the proper manner. Sometimes the trailing edge of the sheet will adhere to the stripper fingers at one side of the press but not at the other side, wherefrom a slewing of the sheet on the delivery tapes, and consequently a failure of proper delivery, may result.

It is the principal object of my invention to obviate the difficulties above referred to by minimizing the opportunity for adhesion between the printed sheet and the stripper fingers owing to static charges. I effect this by reducing the area of the surfaces of the stripper fingers which will be engaged by the sheets during their delivery.

In the accompanying drawing:

Fig. 1 is a side elevation of a stripper finger constructed in accordance with my invention, shown in association with a printing cylinder diagrammatically illustrated; and Fig. 2 is a plan of the finger.

In the drawing, 10 indicates the surface of

a printing cylinder and 11 the ordinary tumbler grippers carried thereby. Placed adjacent the cylinder on the delivery side thereof in the usual manner is a stripper shaft 12 carrying a series of stripper fingers 13, of which only one is shown. The shaft 12 is rocked in a well known manner so that the points of the stripper fingers come into close proximity with the cylinder during the delivery revolution of the latter but are spaced away from the cylinder during the printing revolution.

According to my invention, the upper faces of the stripper fingers are serrated, instead of forming continuous surfaces as has heretofore been customary. Such serrations take the form of teeth 14 which are inclined downwardly from the delivery towards the feeding side of the press. The teeth are also tapered in a vertical plane towards the delivery side of the press, as may be seen from the plan, Fig. 2. Thus points 15 are formed, arranged in line with each other, and the printed sheet passes over and is supported by these points in being delivered from the cylinder.

In the use of stripper fingers constructed as above described the only opportunity for attraction between the fingers and the sheet due to static charges is at the points 15, and these are so small that any sticking effect due to such attraction is negligible. In practice it has been found that the formation of the stripper fingers with serrations as above described entirely does away with all troubles arising from the printed sheets adhering to the stripper fingers.

I claim:

In a printing press, the combination with an impression cylinder of a stripper finger for stripping the printed sheets therefrom and directing said sheets to a delivery device, whereby the printed sheets slide over and past said finger, said finger having the edge thereof formed with a plurality of serrations inclined downwardly towards the cylinder and tapered away from the cylinder on a vertical plane.

In testimony whereof, I sign my name.

BURT FROST UPHAM.
